(57) **CLAIM**

The ornamental design for a vehicle tail light assembly, as shown and described.

DESCRIPTION

FIG. 1 is a front elevational view of the vehicle tail light assembly of the present invention showing my new design;

FIG. 2 is a top plan view thereof;

FIG. 3 is a right side elevational view thereof; and,

FIG. 4 is a left side elevational view thereof.

No claim is made for the rear elevational view thereof.
